Attorney.

UNITED STATES PATENT OFFICE.

RAY FRIEDRICH ALPHONS BERGST, OF DRESDEN, GERMANY.

MUSICAL INSTRUMENT SUCH AS A PIANO OR THE LIKE.

Application filed July 18, 1924. Serial No. 726,673.

To all whom it may concern:

Be it known that I, RAY FRIEDRICH ALPHONS BERGST, a citizen of Germany, residing at Dresden, Saxony, Germany, have invented certain new and useful Improvements in Musical Instruments Such as Pianos or the like, of which the following is a specification.

The present invention relates to a musical instrument (piano or the like) with an arrangement for striking sounding bodies (metal plates, xylophone bars and the like) in which the keyboard of the second instrument is adapted to be placed adjacent to the keys of the stringed instrument.

The additional instrument is displaceable on and adapted to be screwed to the piano or the like. The keys of this instrument rest on the piano keys and are depressed therewith in order that the piano and the instrument may be sounded together.

Heretofore it has been proposed to arrange the additional instrument so that its keys are the uppermost portions of the instrument and the keys are of a length such that flat extensions thereof bear on the piano keys; in accordance with the present invention the additional instrument is arranged above the keys of the piano. Its keys, resting on the piano keys, are in accordance with the invention bell crank levers and are suspended by means of a link in such manner that the striking levers of the additional instrument are swung outwards either by the outward movement of the key lever about the point at which it is bent or by the displacement of the key lever following the swinging of the link.

The invention is illustrated in the accompanying drawing in which Fig. 1 is a vertical section and Fig. 2 a front view.

As shown the casing *a* of the additional instrument is mounted above the keys of the piano *A*. The horizontal support *b* Fig. 2, of the casing is fastened by means of a screw clamp to the side cheeks *B* of the piano.

The keys *d* of the additional instrument rest on the upper side of the black and white keys *C* of the piano. The keys *d* are formed by angle pieces and are each suspended by means of a link *e*. The links are pivotally mounted on a bar *f* secured to the rear wall of the casing *a*. Against the vertical arm

of each angle piece bears the lower end of the striking lever *g* of the additional instrument.

In playing the keys *d* the fingers engage either near the free ends or near the angle of the angle piece. The suspension of the angle pieces in accordance with the invention ensures in both instances proper swinging movement of the striking lever *g*. If the finger touches the outer end of the key lever *d* then the angle *h* presses against the rear wall of the casing *a* which forms a pivot for the lever. If the finger touches the key adjacent the angle *h* the whole angle piece is moved downwards and the link *e* moves into the extended position swinging the angle piece forwardly. The end of the striking lever is entrained in this movement.

On outward swinging movement taking place the free end of the lever *g* comes against a bell crank lever *i* which with its hammer *k* strikes against a projection of the playing hammer *l* and forces this against the sounding plate *m*. All the hammers *l* are mounted in the frame *o* forced by a spring *n* into operative position. The frame can be brought by means of a handle *p* mounted outside the casing (see Fig. 2) against the pressure of the spring *n* into a position in which the hammers *h* miss the projections on the playing hammers *l* so that the additional instrument may be cut out of operation.

Having now particularly described and ascertained the nature of my said invention and in what manner the same is to be performed, I declare that what I claim is:

1. A musical instrument for attachment to a piano, having a playing action, a plurality of angle shaped keys adapted to overlie the keys of a piano and having portions adapted to extend upwardly into said playing action, pivoted links connected to the upper ends of said angle shaped keys and upon which the latter are suspended, said links being normally inclined from a vertical position and said angle shaped keys to be rocked and depressed with the adjacent piano keys, whereby said links direct the upper portions of the angle shaped keys in a horizontal direction, and striker members between the playing action and the upper portions of said angle shaped

keys whereby to manipulate the playing action upon the movement of said angle shaped keys.

2. A musical instrument for attachment to a piano, comprising a casing, means for supporting the casing over the keys of a piano, sounding devices mounted on the casing, a playing action arranged within the casing and including a shifttable frame and 10 strikers pivoted in the frame, operating means arranged in the casing for individually operating said strikers and including striker rods, a plurality of links pivoted in the casing, angle shaped keys suspended on the lower ends of the links and having horizontal portions projecting beneath the casing to overlie the keys of the piano, said 15

striker rods arranged with their lower ends in the paths of the upper ends of said angle shaped keys, said links being normally maintained at an angle to the vertical, 20 whereby depression of said angle shaped keys moves the upper ends of the angle shaped keys downwardly and horizontally against said rods for actuating the playing action.

In testimony whereof I affix my signature in presence of witnesses.

RAY FRIEDRICH ALPHONS BERGST.
